UNITED STATES PATENT OFFICE.

EDWARD THIMGREEN, OF POPOTLA, MEXICO.

MUSIC STAND.

Application filed April 24, 1924. Serial No. 708,709.

To all whom it may concern:

Be it known that I, EDWARD THIMGREEN, a subject of the King of Sweden, residing at Popotla, Distrito Federal, Mexico, have 5 invented certain new and useful Improvements in Music Stands, of which the following is a specification.

This invention relates to certain new and 10 useful improvements in music stands of the type for supporting a continuous strip of sheet music that is wound from one roll to another roll and manually operable.

The primary object of the invention is to 15 provide a music stand carrying journaled rollers upon which a continuous sheet of music is wound with treadle operated mechanism associated with the roller for successively feeding the music sheet from one 20 roller to another and also for reversing the direction of travel thereof.

With the above and other objects in view 25 that will become apparent as the nature of the invention is better understood, the same consists of the novel form, combination and arrangement of parts hereinafter more fully described, shown in the accompanying drawing and claimed.

In the drawing, wherein like reference 30 characters designate corresponding parts throughout the several views,

Figure 1 is a front elevational view, partly 35 in section of a music stand constructed in accordance with the present invention showing the treadle operated mechanism for forwardly feeding and reversing the continuous music sheet,

Figure 2 is a vertical cross-sectional view 40 taken on line II—II of Fig. 1 showing the inclined board or plate over which the music sheet travels,

Figure 3 is a vertical cross-sectional view 45 taken on line III—III of Fig. 1 showing the pulley and belt arrangement for operating the music sheet rolls,

Figure 4 is a detail sectional view taken 50 on line IV—IV of Fig. 7 showing the double pulley block associated with the lower music roll,

Figure 5 is a detail sectional view taken 55 on line V—V of Fig. 7 showing the double pulley block in elevation,

Figure 6 is a detail sectional view showing 60 the spring mounting for the music roll,

Figure 7 is a detail sectional view taken 65 on line VII—VII of Fig. 1 showing the belt connection between the double pulley and

the single pulley associated with one end of the lower music roll,

Figure 8 is a side elevational view of one 60 of the gears for operating the music sheet feeding mechanism,

Figure 9 is a detail sectional view of another form of operating mechanism, and

Figure 10 is a detail sectional view showing 65 the operating gears in side elevation as illustrated in Fig. 9.

The music stand embodies a frame having spaced standards 1 and 2, each embodying a rear wall 3, side walls 4 and a front wall 5, the front wall 5 being provided with a horizontal offset housing 6 intermediate the upper and lower ends thereof while the lower end of the standard is provided with a relatively wide base structure 7 forming a substantial support for the stand, the two 70 base supports 7 of the standard being connected at their lower ends by the cross board 8 as shown in Figs. 1 and 9. The wall formation of each standard provides a housing 9 and the lower end of each inner side wall 4 has an angle wall 10 attached thereto forming a housing 11 open at its forward side and of a form as illustrated in Fig. 2.

The upper ends of the standards are connected by a board 12 over which the sheet music flatly passes, the board being arranged at an inclination as illustrated in Fig. 2 and being carried by the angle brackets 13 secured to the standards with tensioned guide arms or rods 14 associated with the board 12 for holding the sheet music 15 in proper position during travel over the board. A music roll 16 is removably journaled in the upper end of each side standard and another music roll 17 is removably journaled in the outer ends of the offset housings 6, the sheet of music 15 passing from one roll to the other by treadle operated mechanism to be hereinafter described.

A double grooved pulley block 18 is fixed 100 to a stub shaft that is journaled through the inner wall 4 of the upper end of the standard 2 and has a key end for interlocking with the adjacent end of the music roll 16, the opposite end of the roll having a socket 19 to receive the spring pressed pin 20 as shown in Fig. 6 and carried by the upper end of the standard 1 for removably journailling the roll 16 at the upper end of the stand. A 105 similar double grooved roller 21 is journaled in the inner side wall 4 of the standard 2 in

vertical alinement with the pulley 18. A single pulley 22 located in the lower end of the housing 9 of the standard 2 is fixed to one end of the shaft 23 that is journaled in the walls 4 and 10 as shown in Fig. 1 and is in vertical alinement with the outer groove in the upper pulley block 18. An endless belt 24 passes over the inner grooved portions of the pulley blocks 18 and 21 and an endless belt 25 passes over the lower pulley block 22 and over the outer grooved portion of the upper pulley block and spaced from the intermediate pulley block 21 as shown in Figs. 1 and 7. A shaft 26 journaled transversely of the outer end of the housing 6 carried by the standard 2 has a pulley 27 fixed thereto in alinement with the outer groove in the pulley block 21, an endless belt 28 passing over the pulley 27 and the outer grooved portion of the pulley block 21 as shown in Figs. 3 and 7. The end of the shaft 26 projecting through the inner wall 4 of the standard is provided with a key end that is received in a socket in the adjacent end of the music roll 17 while the other end of said music roll is supported in a manner as illustrated in Fig. 6.

As shown more clearly in Figs. 1 and 8, a gear wheel 29 freely supported upon the shaft 23 within the housing 11 encloses a ratchet wheel 30, a tensioned pawl 31 carried by the gear 29 engaging the ratchet wheel 30 to cause rotation of the shaft 23 in one direction when the gear 29 is rotated. The operating means for the gear 29 includes a rack segment 32 fixed to the shaft 33 journaled in the walls 4 and 10, the shaft 33 carrying an angular extension 34 disposed between the standards with a terminal extension 35 extending through the forward open side of the compartment 11. A treadle 36 pivotally mounted at one end as at 37 in the supporting base 7 and normally spring pressed upwardly as at 38 overlies the terminal extension 35 of the shaft 33 and upon lowering movement of the treadle 36 under pressure of a foot, the shaft 33 is rotated to cause the rack segment 32 to be moved into engagement with and rotate the gear 29 by the pawl and ratchet mechanism 31-30, this movement effecting rotation of the shaft 23 and pulley 22 fixed thereon and in turn the several pulleys and belt connections heretofore described for causing the music sheet 15 to be unwound from the roll 17 and wound upon the roll 16, it being noted that the music sheet is fed upwardly of the supporting board 12 in a step by step movement, and at the conclusion of each operation, the spring 38 elevates the treadle 36 and the connection between the treadle and terminal extension 35 of the shaft 33 causes a reverse direction of rotation of the gear 29 with the shaft 23 remaining stationary.

Mechanism is provided for reversing the

direction of rotation of the music rolls 16 and 17 and is adapted to be operated for rewinding the music sheet upon the roll 17 before removal from the stand and includes a shaft 39 journaled in the walls 4 and 10 as shown in Fig. 1 having gears 40 and 41 secured to opposite ends thereof. An idler gear 42 rotatably supported upon the wall 4 meshes with the gear 40, the idler gear 42 in turn meshing with the gear 43 fixed to the shaft 23 in the compartment 9. A shaft 23^a journaled in the walls 4 and 10 associated with the standard 1 carries a fixed gear 44 meshing with the gear 41. A gear and ratchet mechanism 29^a similar to the gear 29 shown in Fig. 8 is associated with the shaft 23^a and a rack segment 32^a secured to the shaft 33^a carries the terminal extension 35^a with which the treadle 36^a is associated. It will therefore be seen that through the interpositioning of the several gears and the operation of the treadle 36^a, reverse rotation of the pulley blocks and belts associated therewith will be effected to cause the music sheet to be rewound upon the music roll 17.

A modification of the invention is shown in Figs. 9 and 10 wherein the lower pulley 22^a is secured to the shaft 23^a within the compartments 9 of the standard 1, a train of three gears 45 being associated with the shaft 23^a while a train of four gears 46 is associated with the shaft 23, the remaining elements of construction and method of operation being the same.

From the above detail description of the device, it is believed that the construction and operation thereof will at once be apparent, and while there are herein shown and described the preferred embodiments of the present invention, it is nevertheless to be understood that minor changes may be made therein without departing from the spirit and scope of the invention as claimed.

What is claimed as new is:

1. In a music stand, a frame, spaced rolls carrying a music sheet journaled on the frame, means for selectively rotating the rolls in reverse directions, said means including a shaft journaled at the lower end of the frame, a gear journaled on the shaft, pawl and ratchet mechanism for locking the gear to the shaft for effecting rotation of the shaft in one direction, a shaft supported rack segment associated with the gear, treadle mechanism for operating the rack segment and belt and pulley connections between the music rolls and gear supporting shaft.

2. In a music stand, a frame, spaced rolls carrying a music sheet journaled on the frame, means for selectively rotating the rolls in reverse directions, an inclined board over which the music sheet travels from one roll to the other roll, said means including a shaft journaled at the lower end of the

frame, a gear journalled on the shaft, pawl and ratchet mechanism for locking the gear to the shaft for effecting rotation of the shaft in one direction, a shaft supported rack segment associated with the gear, treadle mechanism for operating the rack segment and belt and pulley connections between the music rolls and gear supporting shaft.

3. In a music stand, a frame, spaced rolls carrying a music sheet journalled on the frame, means for selectively rotating the rolls in reverse directions, an inclined board over which the music sheet travels from one roll to the other roll, spring devices engaging the opposite edges of the sheet to hold the same in flat contact with the board, said means including a shaft journalled at the lower end of the frame, a gear journalled on the shaft, pawl and ratchet mechanism for locking the gear to the shaft for effecting rotation of the shaft in one direction, a shaft supported rack segment associated with the gear, treadle mechanism for operating the rack segment and belt and pulley connections between the music rolls and gear supporting shaft.

4. In a music stand, a frame, spaced rolls carrying a music sheet journalled on the frame, means for selectively rotating the rolls in reverse directions, said means including a shaft journalled at the lower end of the frame, a gear journalled on the shaft, pawl and ratchet mechanism for locking the gear to the shaft for effecting rotation of the shaft in one direction, a shaft supported rack segment associated with the gear, treadle mechanism for operating the rack segment, belt and pulley connections between the music rolls and gear supporting shaft, said means further including a shaft journalled transversely of the frame, a second treadle operated shaft supported gear on the frame, and gear connections between the transverse shaft and the shaft supporting the treadle operated gears arranged in trains to effect reverse rotation of the music rolls when the last named treadle is operated.

5. In a music stand, a frame, spaced rolls carrying a music sheet journalled on the

frame, means for selectively rotating the rolls in reverse directions, an inclined board over which the music sheet travels from one roll to the other roll, said means including a shaft journalled at the lower end of the frame, a gear journalled on the shaft, pawl and ratchet mechanism for locking the gear to the shaft for effecting rotation of the shaft in one direction, a shaft supported rack segment associated with the gear, treadle mechanism for operating the rack segment, belt and pulley connections between the music rolls and gear supporting shaft, said means further including a shaft journalled transversely of the frame, a second treadle operated shaft supported gear on the frame, and gear connections between the transverse shaft and the shaft supporting the treadle operated gears arranged in trains to effect reverse rotation of the music rolls when the last named treadle is operated.

6. In a music stand, a frame, spaced rolls carrying a music sheet journalled on the frame, means for selectively rotating the rolls in reverse directions, an inclined board over which the music sheet travels from one roll to the other roll, spring devices engaging the opposite edge of the sheet to hold the same in flat contact with the board, said means including a shaft journalled at the lower end of the frame, a gear journalled on the shaft, pawl and ratchet mechanism for locking the gear to the shaft for effecting rotation of the shaft in one direction, a shaft supported rack segment associated with the gear, treadle mechanism for operating the rack segment, belt and pulley connections between the music rolls and gear supporting shaft, said means further including a shaft journalled transversely of the frame, a second treadle operated shaft supported gear on the frame, and gear connections between the transverse shaft and the shaft supporting the treadle operated gears arranged in trains to effect reverse rotation of the music rolls when the last named treadle is operated.

In testimony whereof I affix my signature.

EDWARD THIMGREN.
